CYRUS W. BASSETT, OF MAPLEWOOD, NEW JERSEY, ASSIGNOR TO ELEVATOR SUPPLIES COMPANY, INC., A CORPORATION OF NEW JERSEY.

ELECTRIC SWITCH.

Application filed October 31, 1923. Serial No. 671,841.

The present invention relates to electric switches, and more particularly to a switch adapted to be employed where a rapid and reliable making and breaking of a circuit is desired.

In switches heretofore employed for the purpose of automatically making and breaking circuits as in elevator operating circuits, for instance, wherein the operating circuit is to be broken when the elevator door is opened, considerable annoyance has been experienced due to relatively poor operation of the switches when the parts become worn, and to the necessity of frequently replacing worn parts in the switches.

It is the primary object of the present invention to provide a switch which shall operate extremely rapidly to make or break a circuit without appreciable sparking, and to maintain an efficient contact between the parts when the switch is closed whereby the wear and consequently the cost of maintenance of the switches is appreciably diminished.

26 In the accompanying drawings showing a preferred embodiment of the invention;

Fig. 1 is a view in elevation of the switch with a portion of the cover removed, the switch being shown in closed position;

30 Fig. 2 is a cross-sectional view of the switch through line 2—2 of Fig. 1;

Fig. 3 is a cross-sectional view of the switch taken on the line 3—3 of Fig. 1;

35 Fig. 4 is a view similar to Fig. 1 showing the switch in open circuit position; and

Fig. 5 is a perspective view of the switch shown in operative position as applied to the toggle levers of an elevator door.

Referring in detail to the drawings, 1 is 40 a casing to which suitable lugs 3, 5, having openings therein, are attached, by means of which the casing may be readily mounted in position.

Within the casing are contact blocks or 45 brushes 2, 4 which are mounted upon a block 14 of insulating material such as bakelite, the brushes being held in place by means of metal plates 10, 12, preferably of brass. The plates 10, 12 are fastened to the insulating block 14 by means of screws or other suitable means. The contact blocks 2, 4 may be made of any suitable conducting material, but I prefer to make the blocks of copper graphite and in a form larger at the

base than at the top so as to be readily held in position by means of plates having an opening of a proper size to rigidly hold the said blocks. The plates 10, 12 may have extending portions or terminals 9, 11 to which leads 6, 8, which pass into the casing preferably through openings 18, 20, may be readily attached. In order to avoid coming into contact with or to interfere with the operation of the switch, one lead, as the lead 6, for example, which is attached to the terminal at the lower end of the casing, is passed through a groove or passage 16 in the block 14.

In the lower portion of the casing is a lever or cam member 22 which is preferably mounted so as to turn on and with a pivot 24, which passes through one end of the lever. The pivot 24 is mounted in the covers of the casing, and is attached, externally to the casing, to an arm 25, which is operated by a mechanism to which it is attached. If the switch is used in an elevator circuit, for example, the arm 25 may be attached to a connecting arm 27 which in turn is connected to the toggle lever 29, as shown in Fig. 5 of the drawings, by the movements of which the switch is opened and closed.

In order to operate the switch, to bring the conducting bar 38 in and out of contact with the blocks 2, 4, the bar 38 is flexibly mounted upon a second lever 30, which is operatively connected to the lever 22. The lever 30, which is preferably made of two similar or corresponding parts or sides, is mounted within the casing upon a pivot 32, and is connected to the lever 22 in any suitable manner to cause operation thereof. I preferably mount the lever 22 between the two sides of the lever 30 as shown in Fig. 2 and provide grooves 28 in each side of the lever 30 with which a pin 26 in the lever 22 cooperates, and by means of which the lever 30 is directly operated. Between the parts or sides of the lever 30, and near the upper end thereof, I employ a block or bar 33 of suitable insulating material, preferably of bakelite, in which are parallel openings or holes 34, 36, the function of which will be hereinafter explained. The openings are preferably flared toward the ends or have cross sections in the form of arcs, as shown in Fig. 1 of the drawings, by means of which the bar 38 may adjust itself at any angle,

within certain limits, with the lever 30. A conducting member 38 of suitable conducting material, such as brass or copper, and adapted to bridge the space between the contact blocks, is employed to make and break the circuit through the terminals by bringing the conducting member in and out of contact therewith. In order to insulate the conducting member from other parts of the switch, a suitable non-conductor 37 is attached to the upper side thereof, or the side away from the brushes or contact blocks. The conducting member 38 may be made of a sheet of metal bent upwardly at the sides so as to hold the insulating block 37. Mounted upon the block 37 or insulated portion of the conducting member are two threaded bolts or screws 40, 42 which are adapted to pass through openings 34, 36 in the block 33, and to slide therein. The movement of the lever on the bolts 40, 42 is limited by means of nuts 44, 46 which are attached to the outer portion of the screws. The nuts may be adjusted in position upon the screws and held by means of lock nuts 45, 47 as shown in the drawings, whereby contact may be made between the upper surface of the lever and the nuts at any predetermined position of the lever with respect to the conducting member, and thereby control the making and breaking of the circuit by controlling the position of the point of contact of the conducting member 38. Between the blocks 33 and 37 is a spring 48 which is preferably maintained in compression by means of which the conducting member may be firmly held in contact with the brushes of contact blocks 2, 4 when a lever is moved so as to attain contact. The spring is preferably held in place by inserting it into openings or holes in the blocks 33 and 37. The openings 34, 36 are of such a size with respect to the bolts and in such a position with respect to the lever that when the lever is brought into closed position of the switch the conducting member 38 will be moved longitudinally with respect to the brushes 2, 4 so as to attain a wiping contact between the brushes and the conducting member, whereby a clean surface and a substantially perfect contact may be maintained. In other words, when the switch is closed by means of the swinging of the lever 30 through an arc around the pivot 32 the conducting member is brought into contact with the brushes or contact blocks 2, 4 and thereafter as the lever 30 is forced inwardly by the movement of the lever 22 against the force of the spring 48, the vertical component of the arc through which the outer end of the lever moves or the component parallel to the brushes is taken up by the movement of the conducting member along the upper surface of the brushes or blocks. In order to permit this movement without having the conduct-

ing member raise at one end, the diameter of the openings in the lever through which the bolts pass is made slightly larger than that of the bolts, and are flared at the ends in order to provide the necessary clearance. 70

When the lever 30 is moved away from the conducting member 38 the spring 48 holds the conducting member 38 against the brushes 2, 4 until the upper portion of the lever strikes on the nuts 44, 46 and rapidly pulls the conducting member 38 away from the brushes. The slots 28 in the sides of the lever 30, which by the movement of the pin 26 therein controls the movement of the lever, are so designed that as the lever moves toward the nuts 44, 46, the pin 26 will be in contact with the right hand side of the slot, due to the force of the compression spring 48. At the time the conducting member 38 is ready to leave the brushes 2, 4, or when the upper portion of the lever 30 has reached the nuts 44, 46 on the bolts 40, 42, the pin 26 moves to the other or left hand side of the slot 28 and by its cam action in the slot draws the lever 30 and conducting member 38 rapidly away from the terminals or brushes 2, 4. The movement of the conducting member away from the brushes may be controlled, as desired, by the form of the slot 28 in the lever 30, but it is particularly desirable that at the moment the conducting member 38 leaves the brushes, the movement of the conducting member should be extremely rapid. For this purpose the slot is designed so as to have a projecting portion 52 of such a size and shape that the lever and parts attached thereto will be moved away to its extreme position with a comparatively small throw of the lever 22. Beyond the projecting cam portion 52 the slot is in substantially the arc of a circle with the pivot 24 as its center, whereby substantially no movement of the lever 30 takes place after the pin 26 has reached the circular part of the slot. It is apparent, therefore, that when the switch is applied to the toggle levers of an elevator door, after the conducting member is drawn away from the brushes at the first part of the movement of the toggle levers, there is no further movement of the lever 30 and conducting member 38 during the remainder of the movement of the toggle levers until the same portion of the door stroke is attained in the closing movement thereof. 110

While the switch has been described as being adapted particularly for opening and closing an elevator operating circuit, it is to be understood that the switch may be used in any circuit in which the opening and closing thereof is to be made dependent upon the operation of a lever or other device, and that the switch may be used in any place or for any purpose for which it is adapted. It is to be understood also that various 120 125 130

modifications in the device may be made without departing from the spirit or scope of the invention as defined in the claims.

Having thus described the invention, what is claimed as new is:

1. In an electric switch, a casing, a pair of terminals, conducting blocks connected to said terminals, means for insulating said conducting blocks from each other and from 10 said casing, a conducting member adapted to bridge said conducting blocks, means for moving said member into and out of contact with said blocks, the said means comprising a lever pivoted at one side of said blocks, a slot in said lever, a threaded bolt 15 operatively attached to said conducting means and passing through the slot in said lever, a clearance between said slot and said bolt to permit seating of said conducting 20 means on said terminals in all contacting positions thereof, spring means between said conducting member and said lever whereby said conducting member may be held in contact with said blocks during movement of 25 said lever with respect to said blocks, said bolt cooperating with said lever to move said conducting member longitudinally with respect to said blocks after contact therewith to attain wiping contact between said 30 member and said blocks.
  2. In an electric switch, a casing, contact blocks within said casing, insulating means between said casing and said blocks, means for attaching leads to said blocks, a conducting 35 member adapted to make and break a circuit through said blocks, a lever pivoted at one end and connected to said conducting member, a slot in said lever, a second lever having a pin at one end and pivoted at the 40 other end thereof, said pin operating in said slot to move said slotted lever and said conducting member toward and away from said conducting blocks, a pair of threaded bolts connected to said conducting member and 45 passing through openings in said lever, said openings being of sufficient size to allow play between said lever and said bolts, nuts on said bolts adapted to be placed thereon so as to attain simultaneous contact with 50 said lever when said conducting member is to be withdrawn out of contact with said conducting blocks, and a spring between said lever and said conducting member adapted to hold said conducting member against said 55 conducting blocks when said lever is moved into position to attain closing of the circuit through said blocks and said conducting member.
  3. In an electric switch, a current conducting member and means for positively moving said current conducting member into and out of circuit closing position, com- 60
- prising a pivoted lever, a slotted guide in said lever, a pin movable along said guide, a rocker arm for angularly moving said pin in said guide, and means for relatively disposing said pin and guide so that a uniform rate of angular movement of said rocker arm causes a variable rate of angular movement of said lever and conducting member, said means comprising a plurality of cam faces of different contours in said guide. 65
4. In an electric switch, a terminal, a self-adjusting conducting member having a flat continuous face adapted to contact with said terminal, means for positively moving said conducting member into and out of engagement with said terminal, comprising a lever pivoted at one side of said terminal, a slotted cam-shaped guide in said lever, a pin movable along said guide, a rocker arm for angularly moving said pin in said guide, means for relatively disposing said pin and cam-shaped guide so that a uniform rate of angular movement of said pin causes a variable 70 rate of angular movement of said lever and conducting member, whereby most rapid movement of said conducting member occurs in proximity to said terminals, means for holding said conducting member in pressure 75 contact with said terminal when in engagement therewith, and means for producing transverse sliding contact between said terminal and said conducting member when said lever is operated to move said conducting member into and out of engagement with said terminal. 80
5. In an electric switch, a terminal, a self-adjusting conducting member having a flat continuous face adapted to contact with said terminal, means for positively moving said conducting member into and out of engagement with said terminal, comprising a lever pivoted at one side of said terminal, a slotted cam-shaped guide in said lever, a pin movable along said guide, a rocker arm for angularly moving said pin in said guide, means for relatively disposing said pin and cam-shaped guide so that a uniform rate of angular movement of said pin causes a variable 85 rate of angular movement of said lever and conducting member, whereby most rapid movement of said conducting member occurs in proximity to said terminals, means for holding said conducting member in pressure 90 contact with said terminal when in engagement therewith, and means for producing transverse sliding contact between said terminal and said conducting member when said lever is operated to move said conducting member into and out of engagement with said terminal. 95
